COMBINED VANITY CASE AND LIPSTICK
HOLDER

Murray Klotz, New York, N. Y.

Application July 6, 1949, Serial No. 3,727

Term of patent 14 years

(Cl. D86—10)

To all whom it may concern:

Be it known, that I, Murray Klotz, a citizen of the United States, residing in New York city, in the county of New York and State of New York, have invented a new, original, and ornamental Design for a Combined Vanity Case and Lipstick Holder, of which the following is a specification, reference being had to the accompanying drawing, forming part thereof.

Fig. 1 is a front elevational view of a combined vanity case and lipstick holder showing my design,

Fig. 2 is an elevational side view thereof,

Fig. 3 is a top view of the combined vanity case and lipstick holder shown in Figs. 1 and 2,

Fig. 4 is a perspective view of the combined vanity case and lipstick holder in open position, and

Fig. 5 is a side front view of the lipstick holder in removed position.

I claim:

The ornamental design for a combined vanity case and lipstick holder, substantially as shown.

MURRAY KLOTZ.
